TOBACCO SMOKING PIPE

Maurice Champoux, Quebec, Quebec, Canada

Application January 25, 1935, Serial No. 3,508

1 Claim. (Cl. 131—12)

This invention relates to the broad class of smoker's articles and has reference in particular to a novel and improved tobacco smoking pipe or equivalent article.

5 In introducing this ingenious pipe as a novel contribution to the prior art and trade, I am not unaware of the fact that the idea to be herein-after explicitly covered is not basically new. It follows, therefore, that it is my aim to generally improve upon known types of pipes and the like by providing one which is characterized, I believe, by an unequalled achievement in the way in which it is constructed to trap and subsequently handle dangerous tobacco juices and excess saliva.

Needless to say, the object of the invention is to provide a thoroughly practical and up to date smoking pipe possessing more or less standard features, but improved by the presence therein of exclusive and distinguishing features believed to be indispensable in accomplishing the requisite results with a view toward promoting cleanliness and sanitation, whereby to safeguard the health of the user.

25 Briefly stated, I have accomplished what I desire through the instrumentality of a simple hollow plug serving as a closure as well as a holder for a marketed type of pipe stem cleaner, the bowl and stem of the pipe being slightly revised to accommodate the innovation.

Other features and advantages will become more readily apparent from the following description and drawings.

In the accompanying illustrative drawings 35 wherein like numerals are employed to designate corresponding parts throughout the views:

Figure 1 is a side elevational view of a smoking pipe equipped with the improved safety feature.

40 Figure 2 is a longitudinal sectional view showing the assemblage a little more in detail.

Figure 3 is an exaggerated transverse sectional view through the stem, the section being taken on the plane of the line 3—3 of Figure 2.

45 Figure 4 is a perspective view of the removable closing plug.

Figure 5 is a sectional view of the plug with the removable pipe stem cleaner cooperable therewith.

50 Figure 6 is a view with the assemblage of Figure 5 removed for clearness of illustration of the special bore formation.

Figure 7 is a perspective view of the individual pipe stem cleaner.

55 Figure 8 is a view embodying the features of

Figures 1 and 2 but showing a slightly different proportional arrangement.

In the drawings in Figures 1 and 8 for example, the standard wooden bowl is denoted by the numeral 9 and the stem is indicated at 10 and the removable mouth piece or grip is denoted at 11. These parts may be of different shapes and proportions as the requirements of the trade dictate. In accordance with my invention, however, the parts 9 and 10 are modified. Referring to Figure 6 it will be observed that at the bottom of the bowl I provide a tapered socket 12 to receive the more or less correspondingly shaped wooden plug 13. This plug serves as a combined adapter or holder as well as a closure. The plug has a socketed shank 14 of tapered form which slips into and binds firmly in the socket 12. The outer end 15 is enlarged to provide a head which serves as a convenient knob or finger grip. The socket in the shank 14 is intended to accommodate one end portion of a conventional pipe stem cleaner 16 which is used as the absorbent member. Referring now to Figure 3, it will be observed that the passage in the pipe stem 10 is formed with a duplex bore. The upper part 17 which forms the smoke passage proper is of elliptical cross sectional form while the lower part of the bore indicated at 18 is of cylindrical cross sectional form and serves as a saliva or moisture trap. This feature 18 registers with the socket 12 and is adapted to receive the absorbent cleaner 16. With this arrangement it is evident that the smoke passage 17 registers with the passage in the mouth grip 11. Moreover, it has communication from end to end with the trap 18. The trap 18, however, terminates slightly short of the end of the passage 17 as shown in Figure 2. This serves as a shoulder against which the free end of the absorbent cleaner 16 abuts.

In practice, the pipe stem cleaner is fitted into the socket in the shank 14 of the plug 13. It is held in place more or less by friction. Then, the parts cooperate as shown in Figure 5 to define a convenient unit. This unit is slipped into the passages 12 and 18 and occupies the relationship depicted in Figures 2 and 8. Incidentally, the passage 18 is somewhat the same in cross sectional diameter as the absorbent element 16. Thus, the part 16 serves not only as a pad to take up the moisture but also as a wiper when it is inserted and removed. Obviously, the part 13 is slightly longer than the socket 12 so that the headed end 15 projects sufficiently far beyond the bowl 9 permitted to be grasped for insertion and removal.

- The arrangement, as is obvious, is quite economical and simple. At the same time, it enables the user to buy comparatively inexpensive pipe stem cleaners of the type indicated at 16 5 and to use these in conjunction with the plug 13. Notwithstanding this unusual simplification in assemblage, it is evident that the invention fulfills all of the required purposes and, in fact, apparently transcends in importance and practicability, those structures which utilize metal tubes and other more or less expensive saliva attaching and draining devices.
- It is thought that persons skilled in the art to which the invention relates will be able to obtain a clear understanding of the invention after 10 15 considering the description in connection with the drawings. Therefore, a more lengthy description is regarded as unnecessary.

Minor changes in shape, size and rearrangement of details coming within the field of invention claimed may be resorted to in actual practice, if desired.

Having thus described the invention, what is 5 claimed as new is:

In a structure of the class described, a pipe including a bowl having a stem provided with a passage, the lower portion of the passage being constructed to provide a saliva trap, the lower 10 15 part of said bowl being formed with a socket communicating with said passage, a removable plug in said socket, and an absorbent element carried by said plug and located in said trap, said plug extending for a length in said socket beyond the inner wall of said bowl.

MAURICE CHAMPOUX.
